By his Attorney,

W. Schuster Myers

UNITED STATES PATENT OFFICE.

JOHN T. LENMAN, OF WASHINGTON, DISTRICT OF COLUMBIA.

LETTER-BOX.

SPECIFICATION forming part of Letters Patent No. 404,293, dated May 28, 1889.

Application filed February 8, 1889. Serial No. 299,099. (No model.)

To all whom it may concern:

Be it known that I, JOHN T. LENMAN, a citizen of the United States of America, residing at Washington, in the District of Columbia, have invented certain new and useful Improvements in Letter-Boxes, of which the following is a specification, reference being had therein to the accompanying drawings.

10 My invention relates to an improved letter-box in which there is a tilting tray that divides the lower and upper portion of the box while it is in position to receive the mail-matter, and which closes the letter-opening when 15 it is tilted to deposit the mail-matter into the lower portion of the box, the lid to the letter-opening being raised and lowered by the movements of the tray.

15 The invention will first be described in connection with the accompanying drawings, and then pointed out in the claims.

20 Figure 1 of the drawings is a front elevation of the box, partly broken away, with the tray in tilted position. Fig. 2 is a vertical section of the box, taken through the line α α of Fig. 1, looking to the right. Fig. 3 is a sectional view on the line y y of Fig. 1, showing the tray in its horizontal position.

25 Referring to the drawings, A represents the box having the usual drop-door, A', at one end. The lower portion of the box is rectangular, while its upper portion is rounded, as shown, and the front face is curved inwardly, as at a, thus rendering the upper portion smaller in 30 transverse section than the lower portion.

35 In the front face of the upper portion of the box there is a longitudinal letter-opening, C, of a size to admit the largest-sized envelopes, and the opening is covered by a lid, D, hinged 40 to the box under an overhanging ledge, a'. On the under side of this lid, near its upper end, there is formed an upwardly-curved lug, d, which moves in a small slot, s, (shown in dotted lines in Fig. 1 and in full lines in Fig. 2,) 45 at one side of the letter-opening, for a purpose which will hereinafter appear.

50 E represents the tray, pivoted at e in the rounded portion of the box, and comprising a bottom, 1, sides 2, and front plate, 3. The tray, as will be seen in Fig. 3, is of such length and width that when in a horizon-

tal position it will fill the space between the four walls of the box. The front ends of the side pieces, 2, describe an arc of a circle coincident with the circular portion of the box, 55 and are joined together by the front plate, 3, secured thereto. This plate does not extend down to the bottom of the tray, but terminates a distance therefrom of about the width of the letter-opening C, leaving an opening, 60 o, through which the mail-matter may be placed in the tray. The rear ends of the side pieces preferably slope down until they are about on a level with the upper surface of the rear end of the bottom of the tray, as shown. 65

F represents a lever pivoted at f to the outside of one of the side pieces, 2, preferably the left side, as shown. The upper end of this lever is hooked, as at 4, and engages with the curved lug d on the lid D; and in 70 its lower end there is a curved slot, 5, through which passes a stud, G, secured in the side of the tray, the outer end of said stud passing through a curved slot, S, in the end of the box, and bearing a knob or handle, H. A rod, 75 6, passed through the box, serves to support the tray when tilted forward, and another rod, 7, prevents the tray from being accidentally tilted backward.

75 It will be understood from the description 80 and drawings that the letter-opening is normally closed both by the lid D, which prevents the entrance of water, and by the front face of the tray. Now when it is desired to mail a letter the handle H is simply drawn 85 upward, lifting the tray, and thereby moving stud G upward in the slot in lever F, which will cause said lever to depress the inner end of lug d and throw up the lid D, so that by the time the opening o in the tray registers 90 with the letter-opening the lid will be fully raised. The mail-matter can then be deposited on the tray, after which, by letting go of handle H, the tray will by gravity tilt forward, deposit the letters in the box, and 95 close the letter-opening. As the tray moves at all points in the arc of a circle, and as its ends are at all times in close contact with the box, it is evident that mail-matter cannot be extracted from the box without violence. The 100 curve in the front side of the box not only adds to the appearance of the box, but it also

affords ample space for the passage of the letters, &c., as they are emptied from the tray.

Having thus described my invention, what I claim as new, and desire to secure by Letters 5 Patent, is—

1. The combination, with a box the upper portion of which is rounded and has a letter-opening, of a tray pivoted in said rounded portion, and mechanism for operating it, (the 10 said tray,) which comprises a bottom piece, side pieces whose front ends describe an arc of a circle coincident with the curvature of the box, and a front plate secured to the side pieces and partly closing the front end of the 15 tray, being of such length and width that when in a horizontal position it will fill the space between the four walls of the box, substantially as described, and for the purposes stated.
2. The combination, with a box having an 20 inward curve from its front side and a rounded upper portion, in which is formed the letter-opening, of a tray pivoted in said rounded portion and arranged to tilt downward at its front end, and mechanism for operating it, (the 25 said tray,) which comprises a bottom piece, side pieces whose front ends describe an arc of a circle coincident with the curvature of the box, and a front plate secured to the side 30 pieces and partly closing the front end of the tray, being of such length and width that when in a horizontal position it will fill the space between the four walls of the box, substantially as described, and for the purposes 35 set forth.

3. The combination, with a box having an inward curve from its front side and a rounded upper portion, in which is formed the letter-opening, and a hinged lid covering said opening, of a tray pivoted in said rounded portion 40 of the box and arranged to tilt downward at its front end, and mechanism for simultaneously raising the tray and lid, the said tray, which comprises a bottom piece, side pieces whose front ends describe an arc of a circle 45 coincident with the curvature of the box, and a front plate secured to the side pieces and partly closing the front end of the tray, being of such length and width that when in a horizontal position it will fill the space between the four walls of the box, substantially as described, and for the purposes set forth. 50

4. The combination, with the box and the tray pivoted therein constructed as described, of the hinged lid which covers the letter-opening, having a lug that extends into the box, a lever pivoted to the tray and engaging at its upper end with said lug, and a stud secured to the tray and passing through the slotted lower end of said lever and a slot in 6c the box, whereby the lid is caused to be raised by the upward movement of the receiving end of the tray, substantially as described.

In testimony whereof I affix my signature in presence of two witnesses.

JOHN T. LENMAN.
